UNITED STATES PATENT OFFICE

CARL A. FLOOD, OF FRAMINGHAM, MASSACHUSETTS, ASSIGNOR TO DENNISON MANUFACTURING COMPANY, OF FRAMINGHAM, MASSACHUSETTS, A CORPORATION OF MASSACHUSETTS

STAPLING MACHINE

Application filed July 13, 1929. Serial No. 377,938.

This invention relates to stapling machines, and more particularly to means for forming and attaching staples such as are used for attaching tickets or similar carriers of indicia to fabric or other material. It is an object of this invention, to improve the construction of apparatus of the class described.

In forming a staple, such as is used for attaching a ticket to a fabric, for example, a burr is inevitably formed on the ends of the staple as a result of cutting the wire or metal ribbon from which the staple is made. These burrs tend to tear or otherwise damage delicate fabrics as the prongs of the staple are inserted therethrough. The cost of removing these burrs and finishing the prongs of each staple to the smoothness of a needle is prohibitive so that, in order to minimize the effects of the damage caused by these burrs, it has heretofore been considered advisable to attach the staple as near to the margin of the fabric as possible. This practice serves merely to restrict the damage to an area near the margin which, in most cases, may be conveniently discarded. Furthermore, not only do the prongs of a staple damage the fabric during attachment, but after the staple has been attached the prongs ordinarily project sufficiently above the fabric to catch in other pieces of fabric, or in the clothing of a person handling the fabric, and in fact, these prongs often injure the fingers of any one handling the fabric.

Some of the more specific objects of the present invention are to provide for attaching a staple to a fabric in such a manner as to avoid injury to the fabric during attachment and also to attach the staple so as practically to eliminate the possibility of injury to other goods or persons due to engagement with a prong of the staple, also to facilitate the accurate determination of the points where the staple prongs will pierce the material relative to the margin or other portion thereof to which they are affixed; to provide for the use of relatively light wire for the staple, even when the staple is to be used on the heavier materials; and to provide for the ac-

curate and uniform shaping of the staple prongs.

These and other objects are effected by my invention, as will be apparent from the following description and claims taken in connection with the accompanying drawings, forming a part of this application, and in which:

Fig. 1 is a face view of a ticket attached to a fabric;

Fig. 2 is a section on the line 2—2 of Fig. 1;

Fig. 3 is a front elevation of a stapling mechanism;

Fig. 4 is a section on the line 4—4 of Fig. 3;

Fig. 5 is a plan view taken on the line 5—5 of Fig. 3;

Fig. 6 is a transverse section taken along the line 6—6 of Fig. 3;

Fig. 7 is a transverse section through one of the needles shown in Figs. 3 and 4;

Figs. 8, 9, 10, 11, 12, 13, and 14 are diagrammatic views showing the sequence of operations which occur during a complete cycle of operation of the apparatus shown in Figs. 3 and 4; and

Fig. 15 is a diagrammatic view showing one position of the staple wedge shown in Figs. 3 and 4.

In accordance with the present invention the material to which a staple is to be attached is first pierced by a suitable needle so as to open the fabric sufficiently to permit a prong of the staple to pass therethrough, care being taken to avoid engagement with the fabric by the staple prong during insertion thereof and thus to avoid damage to the fabric during attachment of a staple. This may be accomplished conveniently by providing a passageway in the needle to receive a prong of the staple so that the needle may serve as a guard for keeping the fabric away from the prong of the staple during the insertion thereof. By employing a needle in this manner it is possible to predetermine accurately the exact place where the staple is to penetrate the fabric. This affords a considerable advantage, especially on lace curtains and like materials where it thus becomes possible to insert the prongs through the natural

openings in the lace. The prongs of the staple are preferably first inserted through the fabric and then through the ticket and are then bent over with their ends directed 5 backwardly, or downwardly toward the ticket and disposed closely adjacent thereto. This brings the ends of the prongs adjacent the ticket where they can not damage the fabric to which the ticket is attached and 10 moreover, if desired, the ends of the prongs may be embedded in the ticket so as to assure positively that they will not damage other materials.

In Figs. 1 and 2 the ticket 10 has been attached 15 to the fabric or other web 11 by means of the staple 12. The prongs 13 of this staple have had their end portions bent backwardly, or downwardly toward the ticket 11 so that the points of the respective prongs are directed 20 toward the ticket and closely adjacent thereto. The backwardly directed points of these prongs may project slightly into the ticket in order to more securely fasten the same to the fabric, if so desired. It is also 25 desirable that the end portions of the respective prongs be bent along a smooth even curve which is free from sharp angles which might form points or other projections that would be apt to engage in other pieces of fabric disposed adjacent to the fabric 11.

The apparatus for forming the staple 12 and also for attaching the ticket 10 to the fabric 11 by means of the staple 12 is shown in Figs. 3, 4, 5, 6, and 7. Considering first 35 the lower halves of Figs. 3 and 4, wherein the staple-forming and driving mechanism is disclosed, it will be observed that this mechanism is carried by a suitable supporting and attaching plate 16, which is adapted to be attached 40 to a staple machine in any approved manner, as for example, by means of screws 17. Mounted in suitable recesses on the upper portion of the plate 16 and held therein by an attaching and guiding plate 18 are a 45 pair of needles 19. These needles are disposed in spaced relation so that they may pierce the fabric 11 and separate the strands thereof to provide a sufficient opening to permit the prongs 13 of the staple 12 to pass therethrough without tearing or otherwise 50 damaging the fabric. These needles also permit the use of a lighter wire for the staple than would otherwise be possible if the wire had to force its own way through the fabric, 55 especially on the heavier materials. In order to accomplish this the needles are provided with longitudinal passages 21 which in the present instance are in the form of grooves opening on the adjacent sides of the respective needles, although of course it will be understood 60 that any suitable passageway which will accommodate a prong of the staple 12 may be provided.

The attaching plate 18, which serves as a 65 clamp for the needles 19, may be supported

in spaced relation with respect to the supporting plate 16 in any approved manner, as by means of attaching screws 22 and 23. The lower portion of the plate 18 serves as a guide for the staple-forming and driving 70 means. As shown more clearly in Fig. 4, a suitable anvil 24, which may be rectangular in section, or of any other desired shape, is arranged to be movable, through a recess 26 in the plate 16, into abutting relation with 75 respect to the plate 18 and directly into the path of advance of the staple-driving means 27 which has a groove 27' in which the portion of the wire forming the head of the staple seats.

The staples may be formed of any approved material S, such as round or flat metal wire or the like, and this material is fed to the apparatus between suitable feeding rolls 28 into a guideway 29 which serves to direct a strip of staple forming material into the space between the plates 16 and 18 and below the anvil 24. This guideway may be conveniently supported on the plate 16 by means of the attaching screw 17. Previous 90 to passing through the rolls 28, the material S is preferably wound on a spool, or other package from which it may conveniently be supplied, so that it will tend to curl downward across the staple-driving head 27. 95

With the anvil 24 in the position shown in Fig. 4 and a strip of staple-forming material disposed beneath the anvil in the manner just described, the staple-driving means 27 is advanced sufficiently to clamp the strip 100 of staple-forming material against the anvil 24. The staple-forming means, which comprises a forked head 31 provided with suitable grooves 32 adapted to form the prongs of a staple by bending a strip of material about the anvil 24, is then advanced. The advance, or upward movement of the head 31 shears the staple-forming strip, to provide a blank of the proper length, by forcing the same past the cutting tool 33, which has its cutting edge 34 disposed adjacent the path of advance of the head 31. As shown, the screw 23 may serve to secure the cutting tool in the proper position, or any other suitable means may be employed. 110

The continued advance, or forward movement of the head 31 bends the staple blank about the anvil 24, and the grooves 32 in the head 31 form the prongs 13 of the staple 12. After the staple has been formed the anvil 24 is withdrawn out of the path of the staple-driving means 27 and the staple-driving means is then advanced upwardly to force the staple through the grooves 21 in the needles 19 and thence through the fabric 11. 120 During this operation the inherent curl of the material S will tend to keep the prongs in grooves 21 of the needles. 125

The manner in which these operations are carried out will be more clearly understood 130

from a consideration of Figs. 8 to 14. In Fig. 8 the staple-forming material has been fed into position beneath the anvil 24 as indicated in Fig. 3. The fabric 11 has also 5 been placed upon the needles. This fabric may be positioned manually by having an attendant thrust the fabric upon the needles 19, or means may be provided for accomplishing this automatically. The next step 10 in the cycle of operations is shown in Fig. 9, wherein the staple-driving means 27 has been advanced upwardly to clamp the strip of staple-forming material against the anvil 24. In Fig. 10 the staple-forming plunger, 15 or head 31 has been advanced upwardly to sever the staple-forming material to the proper length to provide a blank, by forcing the same past the cutting edge 34 of the cutting tool 33, and the grooves 32 in the 20 head 31 have functioned to form the prongs 13 of the staple 12 and to bring these newly formed prongs 13 into register with the longitudinal passageways, or grooves 21 of the needles 19. In Fig. 11 the staple-driving 25 plunger 27 has descended sufficiently to release the wire, or other staple-forming material from the anvil 24, and so that the latter may be withdrawn. The ticket holding and 30 attaching means, indicated generally at 36, has also descended, or advanced somewhat toward the needles 19. In Fig. 12, the ticket holding and attaching means has descended to its lowermost position with the ticket 37 disposed directly above and in close proximity 35 to the points of the needles 19. The points of the needles may enter the ticket, or not, as desired. Advantages of having the needles not enter the ticket consist in 40 that the openings for the staple are then substantially no larger than the prongs of the staple (whereas they would be much larger if the needles pierced the ticket) whereby the staple remains in position more 45 accurately with its turned over points perpendicular to the ticket and removal of the ticket and staple is facilitated. The staple-driving plunger 27 has also advanced to force the staple upwardly with its prongs following 50 the grooves 21 in the needles 19. In this view the points of the prongs of the staple are about to enter the ticket 37. Continued upward movement of the plunger 27 will, therefore, force the prongs of the staple 55 through the ticket as indicated in Fig. 13, after which the staple-driving plunger 27 is allowed to descend to the position shown in Fig. 8 and the staple-forming head 31 is also returned to its initial position and the 60 anvil 24 is again inserted in the path of advance of the staple-driving plunger 27, all as clearly indicated in Fig. 14. The fabric with the ticket attached thereto may then be 65 removed from the ticket attaching means 36 either manually, or otherwise.

The ticket holding and attaching means 36 carries a suitable die head 38 which is composed preferably of the blocks 41 and 42 and is provided with grooves 39 adapted to receive the prongs of the staple, after the latter have passed through the ticket 37, and to bend the respective prongs away from each other and backwardly toward the ticket, so that the end portions of the prongs are directed toward the ticket and are disposed in 70 close proximity thereto. Should it be desired to have the ends of the prongs project slightly into the ticket in order to more securely hold the same and also to preclude any possibility of having a prong engage or 75 otherwise catch upon a piece of material, this may be accomplished by adjustment of either the die block or the staple driver. As previously pointed out, the grooves 39 are so formed as to be free from sharp angles which 80 might impede the progress of the staple or produce a sharp bend which would be more likely to catch on other material. The extreme end portions of the prongs may be caused to incline outwardly, if desired, as 85 indicated by the shape of the grooves 39. Pins 39' form the inner wall of the grooves 39 and are supported by the plate 42 (Fig. 15). These pins may be fixed to the plate 90 42 with their ends free, as shown, to permit the clinched staple to be withdrawn from the free ends of the pins or, if desired, the pins may be arranged to be withdrawn laterally to permit removal of the clinched staple. It 95 will also be apparent that the grooves 39 provide a definite channel through which the prongs may be pushed and this gives a more positive action and results in the production of staples which are more uniform than those obtained with the regular open stapling die 100 such as has been used heretofore.

As shown in the upper halves of Figs. 3 and 4, and also somewhat diagrammatically in Fig. 15, the ticket holding and attaching means 36 comprises a member 40, which may be in the form of a plunger adapted to reciprocate vertically toward and from the points of the needles 19, or this member 40 may be an arm adapted to oscillate up and down, or again, this member 40 may partake 110 of any combination of the above motions which will serve to advance and withdraw the arm with respect to the points of the needles 19. As shown in Figs. 3 and 4 the die head 38 is disposed in a recess 38' and is held to the member 40 in any approved manner, as by means of screws 43. The screws 43 also serve to attach the spring clips 44 to the member 40, and these clips are adapted to press the marginal portion of the ticket 37 115 against the blocks 41 and 42 respectively, these members constituting a suitable abutment means for this purpose.

As the staple is forced upwardly with its prongs in the grooves 21 of the needles, these 120

prongs would ordinarily tend to buckle, or bend out of the grooves 21 as the ends of the prongs enter the die. For the purpose of avoiding an occurrence of this kind, the arm 46 is disposed adjacent the ticket and is provided with slots 46' which register with and are adapted to receive the needles 19 to stiffen the same. The walls of the grooves 46' also serve to keep the prongs of the staples in the grooves 21 of the needle. The arm 46 may be supported in any manner so as to be movable into and out of the path of the staple-driving means 27, but in the present instance this arm takes the form of a bell-crank member which has a lug 47 disposed in the recess 48 in the member 40 and pivotally mounted on a pin 49 traversing said recess. The arm 46 is normally held in position to receive the needles 19 by means of a coil spring 51, which is disposed in a recess 52 in the member 40 and co-acts against a seat 53 provided in the upper arm 54 of the bell-crank member 46. The lower surface of the member 46 is arranged in the form of a wedge, or cam 55 so that, upon engagement by the staple-driving means, the arm 46 will be forced aside against the pressure of the spring 51 (Fig. 15) due to the camming action between the staple-driving means 27 and the cam surface 55.

From the foregoing it will be evident that each of the parts 44 and 46 serves to hold the ticket on the movable head or plunger 40 while the head descends and that by using both means accurate positioning of the ticket relatively to the needles is doubly assured while permitting ready insertion and removal of the ticket from the head, although one means may of course be used without the other if desired.

While the grooves 21 in the respective needles 19 may be only of sufficient depth to permit a prong of the staple to pass therethrough within the body of the needle, these grooves are preferably made of a greater depth than would ordinarily be necessary in order to avoid any possibility of having a burr or other ragged edge on the prong come into engagement with the fabric. It will also be apparent that the fabric may be placed upon the needles when the latter are separated from the upper member 40, so that an operator will have ample opportunity to select a proper location for the staple to penetrate the fabric. By means of this arrangement it is often possible to insert the staple through the natural openings in lace or like materials. Furthermore, since the operator may select the location for the ticket, it will be clear that the ticket may be attached to any portion of the fabric, either adjacent the margin or elsewhere. It will also be observed that the staple first penetrates the fabric and then the ticket so that the ticket is interposed between the fabric

and the ends of the staple prongs and the ticket therefore serves to protect the fabric from being damaged by the prongs, regardless of how the prongs are bent to secure the ticket. This provides a simple and yet 70 efficient way of attaching a flat, non-foldable ticket to any portion of a fabric.

While only one form of this invention has been shown and described, it will be understood that the invention is susceptible to 75 various changes and modifications which will occur to those skilled in the art to which this invention appertains, and that this invention is not limited except as indicated by the appended claims. 80

I claim:

1. In an apparatus of the class described, the combination with fixed needles having grooves therein for guiding the prongs of a staple through fabric, of means for attaching a ticket to the fabric comprising means for holding the ticket in position for attachment, means for advancing the prongs through the ticket, and means for bending the inserted prongs backwardly so that their respective end portions are directed toward the ticket. 85

2. In an apparatus of the class described, the combination with fixed needles having grooves therein for guiding the prongs of a 95 staple through fabric, of means for attaching a ticket to the fabric comprising means for holding the ticket in position for attachment, means for advancing the prongs through the ticket, and means for bending 100 the inserted prongs outwardly away from each other and backwardly so that their respective end portions are directed toward the ticket and in close proximity therewith.

3. In an apparatus of the class described, the combination of one or more fixed needles for piercing fabric placed thereon to separate the strands thereof, means providing a passageway in each needle for a prong of a staple, means for holding a ticket in position 110 for attachment, means for advancing each prong through its respective passageway through the fabric and through the ticket, and means for bending the inserted prong or prongs backwardly so that the end portion 115 or portions thereof are directed toward the ticket and in close proximity therewith.

4. In an apparatus of the class described, the combination of a pair of fixed needles suitably spaced for piercing fabric placed 120 thereon to separate the strands thereof to provide openings for the prongs of a staple, means providing a longitudinal passageway in each needle for the translation of the prong of a staple therethrough, means for holding a ticket in position for attachment and substantially in the plane of the points of the needles, means for advancing a staple, having its prongs disposed in the passageways of the respective needles, through the 125 130

- fabric and through the ticket, and means for bending the inserted prongs for attaching the ticket.
5. A device as set forth in claim 4, wherein means are provided for bending the inserted prongs backwardly so that their end portions are directed toward the ticket and in close proximity therewith.
10. In an apparatus of the class described, the combination of a pair of fixed needles suitably spaced for piercing fabric placed thereon to separate the strands thereof to provide openings for the prongs of a staple, each of the needles having a groove extending longitudinally thereof to provide a passage for guiding a prong of a staple, means for forming a staple, and means for advancing the formed staple with its prongs disposed in the respective grooves.
15. In an apparatus of the class described, the combination of a pair of fixed needles suitably spaced apart for piercing fabric to separate the strands thereof to provide openings for the prongs of a staple, each of the needles having a groove extending longitudinally thereof to provide a passage for guiding a prong of a staple, means for severing a length of material to provide a blank, for bending the blank to form a staple and for directing the prongs of the formed staple into position to register with the respective grooves all with a substantially continuous motion, and means for advancing the prongs through the respective grooves.
20. In an apparatus of the class described, the combination with fixed and movable upper and lower members, of means carried by the relatively movable member for holding a ticket in position for attachment, means carried by the fixed member for impaling material when the fixed and movable members are separated, and means for attaching the ticket to the material.
25. In an apparatus of the class described, the combination with fixed and movable upper and lower members, of means carried by the relatively movable member for holding a ticket in position for attachment, one or more needles carried by the fixed member for impaling material when the fixed and movable members are separated, and means for attaching the ticket to the material.
30. In an apparatus of the class described, the combination with needles having grooves in the adjacent sides thereof for guiding the prongs of a staple, and means for driving a staple, of an arm normally disposed in the path of the staple-driving means and having passages therein to receive the needles for stiffening the latter, means for supporting the arm for movement into and out of the path of the staple-driving means, and means engageable with the staple-driving means for removing the arm to permit continued advance of the staple.
35. The combination as set forth in claim 10 and resilient means for normally holding the arm in the path of advance of the staple-driving means.
40. In an apparatus of the class described, the combination of relatively fixed and movable members, means for holding a ticket on the movable member, spaced needles on the fixed member and having grooves therein for guiding the prongs of a staple, staple-driving means, an arm normally disposed in the path of the staple-driving means and having slots therein to receive the needles for stiffening the latter, means for supporting the arm for movement into and out of the path of the staple-driving means, and means providing a cam surface on the arm for engagement with the staple-driving means for removing the arm during advance of the staple.
45. In an apparatus of the class described, the combination of relatively fixed and movable members, means for holding a ticket on the movable member, spaced needles on the fixed member and having grooves therein for guiding the prongs of a staple, staple-driving means, an arm normally disposed in the path of the staple-driving means and having slots therein to receive the needles for stiffening the latter, means for supporting the arm from the movable member for movement relative thereto and into and out of the path of the staple-driving means, and means providing a cam surface on the arm for engagement with the staple-driving means for removing the arm during advance of the staple.
50. In an apparatus of the class described, the combination of a fixed member, fixed needles on the fixed member and having grooves for guiding the prongs of a staple, the grooves having greater depth than width substantially to enclose the prong of a staple and to enable the body of each needle to hold the strands of a fabric pierced thereby out of contact with the staple during insertion thereof, and means for driving the staple.
55. In an apparatus of the class described, the combination of a fixed support member, needles on the fixed support member and having grooves therein for guiding the prongs of a staple, means for driving the staple, and means for holding a ticket at the points of the needles to receive the staple.
60. In an apparatus of the class described, the combination of relatively fixed and movable members, needles rigid with the fixed member and having grooves therein for guiding the prongs of a staple, means for driving a staple, and means carried by the movable member for bending the prongs of the staple backwardly so that their respective end portions are directed toward material pierced thereby and in close proximity therewith.

17. Apparatus of the class described, comprising fixed needles having grooves for guiding a staple, staple-driving means for advancing a staple through the grooves for driving the staple, and movable means for holding a ticket against the needles to receive the staple. 70
18. Apparatus of the class described, comprising members relatively movable toward and from each other, fixed needles on one of the members, the needles having grooves for guiding a staple, staple-driving means movable relative to the fixed needles for advancing a staple through the grooves, and means on the other of the members for holding a ticket in position to receive the staple. 75
19. In an apparatus of the class described, the combination of a member having a pair of curved grooves each entering and leaving one side thereof, the adjacent ends of the grooves being spaced to receive the prongs of a staple, each groove following a substantially semi-circular course from the staple-receiving end thereof to a point adjacent the exit end, each groove declining outwardly from said point to the exit end thereof for bending the tips of the prongs to cause these tips to reenter a ticket at an inclination to the same, and means for driving a staple through the grooves until the tips of the prongs of the staple protrude from the exit ends of the grooves for engagement with a ticket. 80
20. In an apparatus of the class described, the combination of a member having reversely curved grooves extending into and out of one side thereof for receiving the prongs of a staple and for bending the prongs backwardly to guide the ends thereof through the grooves until they protrude from the end of the latter, means for driving a staple through the grooves, and means for holding a ticket on said one side of said member to receive a staple. 85
21. Apparatus of the class described comprising two heads relatively movable toward and from each other between closed and open positions, means on one head for detachably holding a ticket or the like, and needles mounted on the other head to project toward said ticket with their points in spaced relation to the ticket when the heads are in open position, whereby fabric or the like may be impaled on the needles before the heads move to closed position. 90
22. Apparatus of the class described comprising two heads relatively movable toward and from each other between closed and open positions, means on one head for detachably holding a ticket or the like, grooved needles fixedly mounted on the other head to project toward said ticket with their points in spaced relation to the ticket when the heads are in open position so that fabric or the like may be impaled on the needles before 95
- the heads move to closed position, and means for advancing a staple in the needle grooves through the fabric and ticket. 100
23. In an apparatus of the class described the combination of fixed needles having longitudinal grooves in adjacent sides thereof, the grooves being open and unobstructed at the ends thereof remote from the points of the needles, means for causing the prongs of a staple to enter the latter ends of the grooves and for advancing the prongs of the staple along and within the grooves toward the points of the needles. 105
